UNITED STATES PATENT OFFICE.

CHARLES ADAMS-RANDALL, OF NEW YORK, N. Y.

ELECTRIC CALLING APPARATUS FOR TELEPHONES.

No. 841,476.

Specification of Letters Patent.

Patented Jan. 15, 1907.

Application filed December 22, 1903. Serial No. 186,254.

To all whom it may concern:

Be it known that I, CHARLES ADAMS-RANDALL, a citizen of the United States, residing in the borough of Manhattan, city of New York, county of New York, and State of New York, have invented certain new and useful Improvements in Electric Calling Apparatus for Telephones, of which the following is a specification.

10 This invention relates to an electric calling apparatus for telephones; and its object is to improve the efficiency and adapt the apparatus for use with a telephone system upon a telegraph-line or composite telephony and 15 telegraphy whereby telephone calls can be given without interference with the telegraphic instruments in ordinary use thereon.

In the accompanying drawings, Figure 1 is a diagrammatic view of one form of apparatus embodying my improvements and showing the parts employed at each station. Fig. 2 is a diagram showing particularly one 20 way of connecting the primary and secondary coils of a plurality of induction-coils used in sending signals. Fig. 3 shows another way of connecting the coils, the primaries being connected in independent local 25 circuits.

In the several views like parts are identified by like signs.

A push-button 1 or other convenient circuit-closer for closing the local circuit of the vibrator is included in a local circuit 2, which includes also a source of power 3. 35 Also included in said circuit is the electromagnet 4 of an ordinary vibrating-bell apparatus having its armature or vibrator 5 mounted at one end upon a pivot 6. Said armature is provided with a contact-arm 7 in the usual way, which forms one member of an interrupter, the other member thereof consisting of the adjustable stop or contact 8, which is in the form of a screw tapped into a post 9, insulated from the base 10. Said 40 local circuit is normally open, but readily closed by depressing the push-button or other circuit-closer, which closes the circuit through the electromagnet, said circuit being automatically made and broken by the 45 action of the vibrator so long as the circuit is closed at the push-button.

A second local circuit (designated as 11) includes a source of power 12, a primary 13 of an induction-coil, and an interrupter or

circuit-closer comprising contacts 14 and 15, the former being adjustable. The contact 15 is fixed upon a yielding strip or extension 16, fixed upon the unmounted end of the armature 5 and having its other end adjustably secured, preferably by being caught in a slot 17, formed in a support 18, the latter being adjustable transversely of the spring-strip 16 by means of a screw 19 and slot 20. It will be seen that the strip vibrates with the armature, so that the interrupters or automatic circuit-closers operate alternately—i. e., one closing as the other breaks. In the form shown the circuit 11 is closed by the movement which breaks the circuit 2. The secondary 21 of said induction-coil is connected in the line 22, which also includes at each station a call device 23, which may be either in the form of a bell-buzzer, telephone-receiver, or other suitable form. The line may be grounded at 24 or a metallic circuit 75 may be used.

It will be understood that when the push-button or circuit-closer is operated the armature and interrupter in the circuit 2 vibrate rapidly, and through the interrupter or circuit-closer 14 15 the circuit 11 is rapidly made and broken, whereby alternating electrical impulses are produced in the secondary 21 and in the line 22, said impulses effecting the call 23 at the other end of the line, as herein-after explained, and without interfering with the ordinary telegraphic instruments in use on the same line, as the currents transmitted over the line are of great frequency and of high potential. The rapid impulses are 80 transmitted automatically over the line so long as the circuit 2 remains closed by the signaling or calling key or push-button, whereby long and short signals may be transmitted to designate the office called or single or numerical calls of uniform length can be given. My invention also includes the use of a signaling or calling key in the local circuit 11 or in the line-circuit 22 in lieu of the circuit-closer in circuit 2.

At Fig. 2 it will be seen that two induction-coils are used, the secondaries 25 and 26 being connected in parallel in the line, and the primaries 27 and 28 being connected in parallel in the circuit 11.

In the form shown at Fig. 3 the secondaries, (designated as 29 and 30,) are also connected in parallel in the line; but the prima-

ries 31 and 32 are included in independent local circuits 33 and 34, each having interrupters and each interrupter having one member or contact upon the spring 16, so that both independent circuits are made and broken simultaneously by the movements of the armature 5, the movements of the latter being controlled, of course, by the signaling or calling key 1 before described. The strength of the line-current is thereby increased in proportion to the number of coils and the current energy employed in the local circuit or circuits.

The usual telegraphic instruments are also indicated diagrammatically in Fig. 1, 35 being the key, 36 the switch, 37 the relay-magnet, which may be cut out of the line by a switch 38, 39 being the local sounder-circuit, including the sounder 40 and battery 41, and 42 the relay-armature, which makes and breaks the sounder-circuit. The telegraphic apparatus thus indicated at Fig. 1 or other like telegraphic apparatus for duplex or quadruplex working is practically cut out of the telephone calling-circuit by means of a shunt-circuit 43 around such apparatus, which shunt-circuit includes a suitable condenser 44. A two-way switch 45 is preferably provided, one contact-point of the switch 45 being normally closed to receive a call, the circuit then being from the line 22^a through condenser 44, switch 45 to the call-receiver 23, and thence to earth, as at 24, thus cutting out the resistance of coil 21 when receiving a call. To send a call, the switch 45 is changed to the other contact-point, the circuit then being from line 22^a, through condenser 44, switch 45, to binding-post 47, to coil 21, call-receiving apparatus 23, and thence to earth 24, as before. By this arrangement of circuits a call can be sent or received at all times even through the circuit containing the telegraph-key and other apparatus be open; but if the same is closed and offering two circuits to the currents from the line 22^a, since the condenser offers but a small resistance to the telephone-currents and the telephone-call currents as compared to that offered by the telegraph apparatus and as the telephone-call currents are of great frequency and high potential, only a small percentage passes through the telegraphic apparatus, which therefore is not affected.

55. Variations may be resorted to within the scope of my invention—as, for instance, in lieu of the call-receiver 23 in the main line, shown as a telephone-receiver, a sensitive polarized or telephone relay may be used, 60 controlling a local circuit in which a bell or other suitable call-receiving apparatus may be included and operated by a local-battery current, as and in the manner well known in connection with telegraph-relays and the 65 sounder in a local circuit.

Having thus described my invention, I claim—

1. In a telephonic calling apparatus, two independent local circuits, an automatic resilient vibrator arranged to make and break 70 said local circuits alternately, an electromagnet connected in one of said local circuits attracting said vibrator in one direction, an induction-coil having the primary thereof connected in the local circuit unconnected with 75 the electromagnet and having the secondary thereof connected in a line-circuit, and a suitable receiver connected in the line-circuit and arranged to control a local circuit at the receiving end, said local circuit including 80 a suitable call-receiving apparatus.

2. In a telephonic calling apparatus, two independent local circuits, one of said circuits including an electromagnet and a resilient vibrator arranged to alternately make 85 and break said local circuits, said vibrator comprising a pivoted armature adapted to be attracted by said electromagnet when its circuit is closed, and a resilient extension from said armature having the end secured 90 in such manner as to hold the armature out of contact with the magnet.

3. In a telephonic calling apparatus, two independent local circuits, an electromagnet connected in one of said circuits, an induction-coil having the primary thereof connected in the other local circuit and having 95 the secondary thereof connected in the line-circuit, and a resilient vibrator arranged to make and break said local circuits alternately, said vibrator comprising a pivoted armature disposed adjacent to said electromagnet and having a spring extending from the free end thereof, said spring having its other end adjustably secured so as to hold 105 the armature normally out of contact with said electromagnet.

4. In a telephonic calling apparatus, two independent local circuits, one of said circuits including an electromagnet and a resilient vibrator arranged to alternately make 110 and break said local circuits, said vibrator comprising an armature pivoted at one end and adapted to be attracted by said electromagnet when its circuit is closed, and a resilient extension at the free end of said armature, said resilient extension being adjustably secured at the end remote from the armature in such manner as to hold the armature normally out of contact with the said 115 electromagnet.

5. In a telephonic calling apparatus, two independent local circuits, one of said local circuits including an electromagnet, a resilient vibrator actuated by said electromagnet to make and break said local circuits alternately, and an induction-coil having its primary connected in the local circuit not including the electromagnet and having its secondary connected to line. 125

3. In a telephonic calling apparatus, two independent local circuits, one of said local circuits including an electromagnet, an induction-coil having its primary connected in the local circuit not including the electromagnet and having its secondary connected to line, and a resilient vibrator arranged to make and break said local circuits alternately, said vibrator comprising a pivoted armature and a resilient extension from said armature, the extension having its end fixed and bearing a contact-point for making the local circuit including the primary of the induction-coil.
